DROP INLET FOR EARTH-FILLED DAMS

Joel R. Benjamin, Medina, Ohio; Dorothy E. Benjamin, executrix of said Joel R. Benjamin, deceased

Application May 5, 1950, Serial No. 160,256

4 Claims. (Cl. 61—18)

My invention relates generally to water control devices and is more particularly directed to a drop inlet for earth-filled dams.

An object of this invention is to provide a one package unit drop inlet that can be prefabricated to meet the acreage and run-off conditions of a particular water shed area, before the drop inlet is transported to the dam site.

Another object of this invention resides in providing a drop inlet that is self supporting, requiring no temporary or permanent auxiliary structures, and requiring no time consuming and expensive concrete work.

A further object of this invention is to provide a drop inlet with an adjustable anti-swirl plate at the inlet end of the intake stack, to permit the laying of the discharge pipe in any desired direction, and still keep the anti-swirl plate parallel with the center line of the dam.

A still further object of this invention is to provide a drop inlet with a water tight anti-seep plate mounted on the discharge pipe to prevent the seeping of water along the outside surface of the buried discharge pipe.

A still further object of my invention is to provide a drop inlet with a base plate closing the lower end of the intake stack, and extending out beyond the walls of the stack into the foundation earth, to support the inlet and to overcome buoyancy in deep installations.

Other objects and advantages of this invention will be apparent during the course of the following description.

The accompanying drawing is a cross section view of an earth-filled dam built up around my drop inlet.

When installing my drop inlet in different localities I may use such equivalents and alternatives of construction as the exigencies of varying conditions may demand without departing from the broad spirit underlying this invention.

In the drawing an earth-filled dam is shown at 1. It is placed across a watercourse with an upstream slope at 2. This dam is built up around the drop inlet after it has been assembled and set in place on the foundation earth level 3 over the core trench 4.

The intake stack 5 has a base plate 6 attached to its lower end. The area of the base plate 6 is approximately twice the area of the cross section of the intake stack 5 to prevent it from sinking down into the foundation earth. The base plate 6 also prevents the dropping water from wearing away the foundation earth, and it overcomes buoyancy on deep installations.

The adjustable anti-swirl plate 7 welded to attaching collar 8 is fastened to the intake stack 5 by bolts 9 passing thru holes in the collar brackets 10. This adjustable anti-swirl plate 7 permits the discharge nipple 11 to be pointed in any desired downstream direction. The face of the anti-swirl plate 7 may thus be set flush with the earth dam 2 and parallel to its center line, so that the plate can perform its function of protecting the earth from erosion by the swirling water at the entrance of the intake stack 5. Anchor rods 12 attached to the anti-swirl plate 7 extend to the upstream slope at 2.

The discharge tail pipe 13 is attached to the discharge nipple 11 by the waterproof metal coupling 14. The seal at this junction is obtained by painting the outside of the discharge nipple 11 and discharge tail pipe 13 with an asphalt compound. The waterproof coupling 14 is drawn tight and retained by metal rods 15 wrapped around it and passing thru conventional silo lugs 16. The metal rods 15 are threaded on the ends to receive 80 nuts that are pulled up against the silo lugs 16.

2

The upper anti-seep plate 17 and the lower anti-seep plate 18 are each welded to a half-collar 19. The two anti-seep plates overlap when assembled on the discharge tail pipe 13. The half-collars 19 are held together by bolts 20 passing thru collar brackets 21. The purpose of the anti-seep plate is to prevent the removal of foundation earth by water seeping along the discharge tail pipe 13. The core trench 4 is filled with a non-porous clay to prevent the seepage of water thru the foundation earth.

After the drop inlet structure is completely assembled on the foundation earth, the earth dam 1 is filled in up to the level of crest 22, continuing the clay core 23 above the core trench 4.

In summary, it will be understood that the present invention provides a novel drop inlet which includes an adjustable anti-swirl plate, a base plate, and an anti-seep plate furnished as integral parts of a package unit drop inlet and installed on the apparatus at the time of its fabrication. This results in the elimination of expensive and time consuming concrete work, and makes it financially practical to install small water and soil conserving dams and ponds in areas not readily accessible.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

I claim:

1. A drop inlet construction in combination with an earth-filled dam forming a confining wall or embankment for a body of water, comprising an upright stack vertically disposed within said earth-filled dam; a laterally extending discharge pipe leading from the lower portion of said stack; a waterproof anti-seep plate mounted on said discharge pipe intermediate the ends thereof; an anti-swirl plate mounted on the upper portion of said stack; a base plate closing the lower end of said stack, said plate being of greater area than the end of the stack so as to extend outwardly beyond the walls of the stack to anchor the drop inlet against flotation by buoyancy forces exerted on the drop inlet by surrounding water.

2. A drop inlet construction in combination with an earth-filled dam forming a confining wall or embankment for a body of water, comprising an upright stack vertically disposed within said earth-filled dam; a laterally extending discharge pipe leading from the lower portion of said stack; a base plate closing the lower end of said stack, said plate being of greater area than the end of the stack so as to extend outwardly beyond the walls of the stack to anchor the drop inlet against flotation by buoyancy forces exerted on the drop inlet by surrounding water.

3. A drop inlet construction in combination with an earth-filled dam forming a confining wall or embankment for a body of water, comprising an upright stack vertically disposed within said earth-filled dam; a laterally extending discharge pipe leading from the lower portion of said stack; an anti-swirl plate mounted on the upper portion of said stack; a base plate closing the lower end of said stack, said plate being of greater area than the end of the stack so as to extend outwardly beyond the walls of the stack to anchor the drop inlet against flotation by buoyancy forces exerted on the drop inlet by surrounding water.

4. A drop inlet construction in combination with an earth-filled dam forming a confining wall or embankment for a body of water, comprising an upright stack vertically disposed within said earth-filled dam; a laterally extending discharge pipe leading from the lower portion of said stack; a waterproof anti-seep plate mounted on said discharge pipe intermediate the ends thereof; a base plate closing the lower end of said stack, said plate being of greater area than the end of the stack so as to extend outwardly beyond the walls of the stack to anchor the drop inlet against flotation by buoyancy forces exerted on the drop inlet by surrounding water.
